BUCKLE AND TIMEPIECE

The present application is based on, and claims priority from JP Application Serial Number 2021-110101, filed Jul. 1, 2021, the disclosure of which is hereby incorporated by reference herein in its entirety.

BACKGROUND

1. Technical Field

The present disclosure relates to a buckle used in a band such as a timepiece band and a band for an ornamental accessory, and a timepiece including the buckle.

2. Related Art

Some related-art buckles used in wristwatch bands include a device that allows fine adjustment of the length of the band (see JP-A-2015-164567, for example).

The buckle described in JP-A-2015-164567 includes a push button that is located at the rear surface of a buckle cover and releases a locking mechanism of a band length adjustment mechanism. When the push button is pressed, an end link coupled to a bracelet becomes movable relative to the buckle cover so that the length of the bracelet can be adjusted.

The buckle described in JP-A-2015-164567 requires operation of the push button at the rear surface of the buckle cover to adjust the band length, and the button operation is cumbersome. Furthermore, the buckle is formed of a large number of parts, resulting in another problem of an increase in cost.

SUMMARY

A buckle according to an aspect of the present disclosure is a buckle that links a first band and a second band to each other, the buckle including a folding member linked to the first band, a buckle cover pivotably linked to the folding member, a slide plate supported slidably relative to the buckle cover in a longitudinal direction of the first band and the second band and linked to the second band, a swing arm rotatably supported by the buckle cover, and a spring that urges the swing arm. The slide plate has a plurality of groove sections provided along the longitudinal direction. The swing arm includes an engagement click engageable with any of the groove sections of the slide plate and is supported rotatably in a first rotational direction in which the engagement click engages with any of the groove sections and in a second rotational direction in which the engagement click separates from the groove section. The spring urges the swing arm in the first rotational direction. The folding member restricts rotation of the swing arm in the second rotational direction when the folding member is accommodated in the buckle cover, and cancels the restriction of the rotation of the swing arm in the second rotational direction when the folding member is detached from the buckle cover.

A timepiece according to another aspect of the present disclosure includes the buckle described above.

BRIEF DESCRIPTION OF THE DRAWINGS

FIG. 1 is a front view showing a wristwatch according to an embodiment.

FIG. 2 is a perspective view showing a buckle with a folding member according to the embodiment folded.

2

FIG. 3 is a perspective view showing the buckle with the folding member according to the embodiment unfolded.

FIG. 4 is an exploded perspective view of the buckle according to the embodiment.

5 FIG. 5 is a partially exploded perspective view showing the rear side of a buckle cover according to the embodiment.

FIG. 6 is a perspective view showing a slide plate according to the embodiment.

10 FIG. 7 is a perspective view showing a swing arm according to the embodiment.

FIG. 8 is a partially exploded perspective view showing a button unit according to the embodiment.

FIG. 9 is a perspective view showing key parts of the locked buckle in the embodiment.

15 FIG. 10 is a side view showing the key parts of the locked buckle in the embodiment.

FIG. 11 is a side view showing the key parts of the unlocked buckle in the embodiment.

20 FIG. 12 is a side view showing a band length adjustment state in the embodiment.

FIG. 13 is a side view showing another band length adjustment state in the embodiment.

25 FIG. 14 is a side view showing another band length adjustment state in the embodiment.

FIG. 15 is a side view showing a maximum band length state in the embodiment.

30 FIG. 16 is an enlarged view showing key parts of the slide plate and the swing arm according to a variation.

DESCRIPTION OF EXEMPLARY EMBODIMENTS

An embodiment of the present disclosure will be described below with reference to the drawings.

35 A wristwatch 100 as a timepiece includes an exterior case 10, a first band 11, and a second band 12, as shown in FIG.

1. Lugs 10A are provided as parts integrated with the exterior case 10 at 6-o'clock and 12-o'clock sides thereof. The first band 11 is linked to the 6-o'clock-side lugs 10A 40 with an attaching pin, and the second band 12 is linked to the 12-o'clock-side lugs 10A with another attaching pin.

The first band 11 and the second band 12 are each formed of a plurality of band pieces 9 linked to each other with pins that are not shown.

45 The free ends of the first band 11 and the second band 12 are fastened to each other via a buckle 1 shown in FIGS. 2 to 5.

The buckle 1 is a three-fold buckle including a folding member 2. FIG. 2 is a perspective view of the buckle 1 with the folding member 2 folded and accommodated in the buckle 1. FIG. 3 is a perspective view of the buckle 1 with the folding member 2 unfolded. FIG. 4 is an exploded perspective view of the buckle 1. FIG. 5 is a partially exploded perspective view showing the rear side of a buckle cover 40.

50 FIG. 6 is a perspective view of a slide plate 50. FIG. 7 is a perspective view of a swing arm 60. FIG. 8 is a perspective view of a button unit 70. FIG. 9 is a perspective view showing key parts of the locked buckle 1. FIG. 10 is a side view showing the key parts of the locked buckle 1.

55 It is assumed in each of the figures that an axis X is an axis extending along the longitudinal direction of the first band 11 and second band 12, that an axis Y is an axis perpendicular to the axis X and extending along the width direction of the first band 11 and the second band 12, and that an axis Z is an axis perpendicular to the axes X and Y. The directions of the axis X are defined as follows: a direction X1 is the

direction from the buckle **1** toward the first band **11**; and a direction **X2** is the direction from the buckle **1** toward the second band **12**. The directions of the axis **Y** are defined as follows: a direction **Y1** is the direction from the center of the buckle cover **40** in the width direction toward a first sidewall section **42**; and a direction **Y2** is the direction from the center toward a second sidewall section **43**. The directions of the axis **Z** are defined as follows: a direction **Z1** is the direction from the folding member **2** toward the buckle cover **40**, that is, toward the front surface of the buckle **1**; and a direction **Z2** is the direction from the buckle cover **40** toward the folding member **2**, that is, toward the rear surface of the buckle **1**. In each part of the buckle **1**, a surface facing the direction **Z1** is called as a front surface, and a surface facing the direction **Z2** is called a rear surface in some cases.

The buckle **1** includes the folding member **2** and a buckle body **4**, as shown in FIGS. 2 to 4.

The folding member **2** includes a middle plate **20** and an outer plate **30**.

The middle plate **20** is a member elongated along the axis-X direction, which is the longitudinal direction of the first band **11**, and the end of the middle plate **20** in the direction **X1** is pivotably linked to the first band **11**, as shown in FIGS. 3 and 4. The end of the middle plate **20** in the direction **X2** is pivotably linked to one end of the outer plate **30**.

The middle plate **20** is provided with a hook **21**. The hook **21** is provided at the front surface of the middle plate **20** in the vicinity of an end of the middle plate **20**, the end linked to the first band **11**. The hook **21** includes a protruding section **22**, which protrudes in the direction **Z1**, and a click section **23**, which protrudes in the direction **X2** from the protruding section **22**. The front surface of the click section **23** is an inclining surface **23A**, which inclines in the direction **Z2**, that is, downward as extending in the direction **X2**, as shown in FIGS. 3 and 10. A stepped section **25** having a recessed surface is formed in an intermediate portion of the middle plate **20** in the longitudinal direction.

The end of the outer plate **30** in the direction **X1** is pivotably linked to the buckle cover **40** with a spring rod **31**. The outer plate **30** includes a shaft **32**, through which the spring rod **31** is inserted, bodies **33**, which extend from the shaft **32** along the axis-X direction, which is the longitudinal direction of the bands, and disposed on the right and left sides of the middle plate **20**, and a linker **34**, which links the bodies **33** to each other and has a convex rear surface placed at the stepped section **25** of the middle plate **20**, as shown in FIG. 4.

The hook **21** of the middle plate **20** is therefore provided so as to protrude in the direction **Z1** through one opening between the bodies **33** of the outer plate **30** when the folding member **2** is folded. Portions of the middle plate **20** other than the stepped section **25** thereof are located in the openings between the bodies **33** of the outer plate **30**, and the front surfaces of the middle plate **20** and the outer plate **30** are configured to be located substantially in the same plane, and so are the rear surfaces thereof.

Configuration of Buckle Body

The buckle body **4** includes the buckle cover **40**, the slide plate **50**, the swing arm **60**, and the button unit **70**, as shown in FIGS. 2 to 4.

The buckle cover **40** has a plate-shaped front surface section **41**, which is arcuately curved along the directions **X1** and **X2**, which are the directions in which the slide plate **50** slides, and the first sidewall section **42** and the second sidewall section **43**, which protrude from the outer edges of

the front surface section **41** in the directions **Y1** and **Y2** toward the rear side of the buckle cover **40**, as shown in FIGS. 4 and 5.

A guide rail section **411**, which continuously extends in the axis-X direction, is formed at the rear surface of the front surface section **41**.

Guide grooves **44**, which guide the slide plate **50** in a slideable manner, and through holes **46**, through which a first button **71** and a second button **72** of the button unit **70** are inserted, are formed at the first sidewall section **42** and the second sidewall section **43**. The outer-surface-side opening of each of the through holes **46** has an elliptical shape, and the inner-surface-side opening of the through hole **46** has a rectangular shape and is larger than the outer elliptical opening; the two openings are formed in accordance with the shapes of the first button **71** and the second button **72**.

Furthermore, the first sidewall section **42** and the second sidewall section **43** each have a hole **48**, to which the spring rod **31**, to which the outer plate **30** is linked, is attached, and a through hole **49**, through which a pin **68**, which serves as a shaft to which the swing arm **60** is rotatably attached, is inserted.

The slide plate **50** is disposed between the buckle cover **40** and the folding member **2** and provided so as to be slideable along the guide grooves **44** of the buckle cover **40** in the directions **X1** and **X2**, which are the longitudinal direction of the first band **11** and second band **12**, as shown in FIGS. 2 to 4.

The slide plate **50** includes a plate section **51**, which has right and left ends disposed in the guide grooves **44** described above, a linkage section **52** formed at an end of the plate section **51**, and groove sections **53** and a movement restriction section **54**, which are formed at the front surface of the plate section **51**, as shown in FIG. 6. The slide plate **50** has a front end that is the end which faces the direction **X1** and where the movement restriction section **54** is formed, and a rear end that is the end which faces the direction **X2** and where the linkage section **52** is formed. A through hole **52A** is formed in the linkage section **52**, and a linkage pin to which the second band **12** is linked is inserted through the through hole **52A**.

The plurality of groove sections **53** are each an inverted triangular V-shaped groove extending in the width direction of the slide plate **50**, that is, in the axis-Y direction, and are successively provided in the sliding direction of the slide plate **50**, that is, in the axis-X direction. The groove sections **53** are each formed of a first inclining surface **531** and a second inclining surface **532**. The first inclining surface **531** is an inclining surface of each of the groove sections **53**, the inclining surface facing the linkage section **52**, that is, facing the direction **X2**, and the second inclining surface **532** is an inclining surface of each of the groove sections **53**, the inclining surface facing the movement restriction section **54**, that is, facing the direction **X1**. The first inclining surface **531** and the second inclining surface **532** each have an inclination angle of 60 degrees with respect to the direction of movement of the slide plate **50** and have the same inclination angle.

The movement restriction section **54** is a protruding section formed continuously with the groove sections **53** on the side thereof facing the direction **X1**, having a substantially rectangular cross section, and continuously extending in the width direction of the slide plate **50**. The movement restriction section **54** protrudes upward beyond the upper ends of the second inclining surfaces **532** of the groove sections **53**, that is, toward the surface section **41**. A side surface of the movement restriction section **54**, the surface

facing the second inclining surfaces 532, is a restriction surface 54A perpendicular to the direction in which the slide plate 50 moves.

The swing arm 60 is disposed between the front surface section 41 of the buckle cover 40 and the slide plate 50 and pivotably attached to the buckle cover 40 via the pin 68, which has the shape of a round rod and is inserted through and fixed in the through holes 49 in the first sidewall section 42 and the second sidewall section 43, as shown in FIGS. 2 to 4. As the structure that fixes the pin 68 to the first sidewall section 42 and the second sidewall section 43, a ring-shaped fixing member or any other component may be press-fit into and fixed in the gap between the pin 68 and each of the through holes 49, or the pin 68 may be screwed into the through holes 49, that is, the pin 68, which serves as the axis of rotation, only needs to be fixed so as not to come off the through holes 49.

The swing arm 60 includes a base 61, which is rotatably supported by the pin 68, an arm section 62, which extends from the base 61 in the direction X2, that is, toward the slide plate 50 and has an engagement click 63, and a restriction strip 64, which extends from the base 61 in the direction X1, as shown in FIG. 7.

The base 61 includes a pair of support walls 611, through which the pin 68 is inserted, and a linkage wall 612, which links the support walls 611 to each other. A torsional spring 65 is disposed between the support walls 611. The torsional spring 65 includes first contact sections 651, which are disposed inside the support walls 611 and are in contact with an upper end portion of the linkage wall 612, coil sections 652, through which the pin is inserted, and a second contact section 653, which protrudes toward the button unit 70.

The arm section 62 extends in the direction X2 from an upper portion of the base 61, that is, the side facing the front surface section 41 of the buckle cover 40. The arm section 62 is therefore disposed along the front surface section 41.

The engagement click 63 has a first perpendicular surface 631 and a second perpendicular surface 632 so provided as to extend from the front end of the arm section along the direction Z2, which is substantially perpendicular to the direction X2, which is the direction in which the arm section 62 extends, and a first inclining surface 633 and a second inclining surface 634. The first perpendicular surface 631 is the outer surface facing the linkage section 52 of the slide plate 50, and the second perpendicular surface 632 is the inner surface facing the movement restriction section 54 of the slide plate 50.

The first inclining surface 633 is formed continuously with the first perpendicular surface 631, and the second inclining surface 634 is formed continuously with the second perpendicular surface 632. The first inclining surface 633 and the second inclining surface 634 incline toward each other as approaching the front ends thereof, and form a triangular-shaped click section in a side view viewed in the axial direction of the pin 68, which is the axis of rotation of the swing arm 60.

The restriction strip 64 extends in the direction X1 from a lower portion of the base 61, that is, from the side facing the folding member 2. The arm section 62 and the restriction strip 64 are therefore disposed so as to sandwich the pin 68, which serves as the axis of rotation of the swing arm 60. Therefore, when the arm section 62 rotates in a first rotational direction R1, in which the arm section 62 approaches the slide plate 50, the restriction strip 64 rotates in the first rotational direction R1, in which the restriction strip 64 moves away from the folding member 2. When the arm section 62 rotates in a second rotational direction R2,

which the arm section 62 moves away from the slide plate 50, the restriction strip 64 rotates in the second rotational direction R2, in which the restriction strip 64 approaches the folding member 2.

5 The button unit 70 includes the first button 71, the second button 72, and a lock member 80, as shown in FIGS. 2 to 5 and FIG. 8.

The first button 71 and the second button 72 protrude via the through holes 46 in the first sidewall section 42 and the 10 second sidewall section 43, respectively, and are movably disposed in the axis-Y direction.

The first button 71 includes a base plate 710, a first operation section 711 protruding in the direction Y1 from the base plate 710, and a guide section 712 protruding in the 15 direction Y2 from the base plate 710, as shown in FIG. 8. The first operation section 711 is inserted through the through hole 46 in the first sidewall section 42 and protrudes out of the buckle cover 40. The base plate 710 is disposed in the inner-surface-side opening of the through hole 46 in 20 the first sidewall section 42 and comes into contact with the wall surrounding the elliptical opening to restrict movement of the first button 71 in the direction Y1.

The guide section 712 is formed in the shape of a flat plate and has two side surfaces, a guide surface 712A and a side 25 surface 712B. The guide surface 712A is a side surface facing the direction X2, that is, facing the base 61 of the swing arm 60, and inclines in the direction X1, in which the guide surface 712A separates away from the base 61, that is, approaches the side surface 712B, which is the other side 30 surface, as extending in the direction Y2.

The second button 72 includes a base plate 720, a second operation section 721 protruding in the direction Y2 from the base plate 720, and a guide section 722 protruding in the 35 direction Y1 from the base plate 720, as the first button 71 does. The second operation section 721 is inserted through the through hole 46 in the second sidewall section 43 and protrudes out of the buckle cover 40, and the base plate 720 is disposed in the inner-surface-side opening of the through hole 46 to restrict movement of the second button 72 in the 40 direction Y2.

The guide section 722 is formed in the shape of a flat plate and has a guide surface 722A and a side surface 722B, as 45 also shown in FIG. 4, like the guide section 712. The guide surface 722A inclines in the direction X1, that is, in the direction in which the guide surface 722A approaches the side surface 722B, which is the other side surface, as extending in the direction Y1, as the guide surface 712A does.

The lock member 80 includes an upper surface section 81 50 provided on the side facing the front surface section 41, a lower surface section 82 provided on the side facing the folding member 2, and a guidance section 83 provided between the upper surface section 81 and the lower surface section 82, as shown in FIG. 8.

55 A guide groove 811 formed along the axis-X direction is formed at the front surface of the upper surface section 81. The lock member 80 slides in the axis-X direction with the aid of the guide rail section 411 on the rear side of the front surface section 41 and the guide groove 811.

A first side surface 84 of the lock member 80, the side 60 surface facing the direction X2, is a flat surface, and the second contact section 653 of the torsional spring 65 is in contact with the first side surface 84, as also shown in FIG. 10. The torsional spring 65 is so disposed that the first contact sections 651 are in contact with upper end portions 65 of the linkage wall 612 of the swing arm 60, that is, portions shifted in the direction Z1 from the pin 68, which is the axis

of rotation, and the second contact section 653 is in contact with the first side surface 84 of the lock member 80. The torsional spring 65 therefore urges the swing arm 60 in the first rotational direction R1 and the lock member 80 in the direction X1.

A second side surface 85 of the lower surface section 82, the side surface facing the direction X1, is an inclining surface that inclines so as to protrude in the direction X1 as extending in the direction Z1. The front surface of the lower surface section 82 is a locking surface 821, which locks the hook 21, as shown in FIGS. 9 and 10.

The guidance section 83 has a pair of guidance surfaces 831, which incline toward each other as extending in the direction X1. The guide surface 712A of the first button 71 and the guide surface 722A of the second button 72 come into contact with the guidance surfaces 831. The guide sections 712 and 722 are disposed between the upper surface section 81 and the lower surface section 82, which restrict movement of the guide sections 712 and 722 in the axis-Z direction.

The lock member 80 is urged in the direction X1 by the torsional spring 65, and the first button 71 and the second button 72 are urged to separate away from each other in the directions Y1 and Y2 when the guidance surfaces 831 come into contact with the guide surfaces 712A and 722A. The base plates 710 and 720 are then maintained being in contact with the first sidewall section 42 and the second sidewall section 43, respectively, that is, the first operation section 711 and the second operation section 721 are maintained protruding out of the buckle cover 40. In this case, the lock member 80 has moved to a locked position where the locking surface 821 can lock the click section 23 of the hook 21.

On the other hand, when a user pushes the first button 71 and the second button 72 in the direction in which the two buttons approach each other, the guide surface 712A of the guide section 712 and the guide surface 722A of the guide section 722 come into contact with the guidance surfaces 831, causing the lock member 80 to move in the direction X2 against the urging force produced by the torsional spring 65 to unlock the hook 21 from the locking surface 821. In this case, the lock member 80 has moved to an unlocked position where the hook 21 is unlocked.

How to Attach and Detach Wristwatch

How the user wears the wristwatch 100 around the user's wrist will next be described.

With the buckle 1 unlocked and the folding member 2 unfolded, as shown in FIG. 3, the user inserts a wrist through the space formed by the first band 11 and the second band 12, and pushes the buckle cover 40 toward the folding member 2 while folding the folding member 2. The hook 21 of the middle plate 20 thus comes into contact with the lock member 80 through one of the openings of the outer plate 30. In this process, the inclining surface 23A of the hook 21 and the inclining second side surface 85 of the lock member come into contact with each other, and the inclining surfaces each cause the lock member 80 to move in the direction X2 so that the click section 23 climbs over the lower surface section 82. The urging force produced by the torsional spring 65 then moves the lock member 80 back in the direction X1, and the click section 23 comes into contact with the locking surface 821 and is locked thereby. The folding member 2 is thus accommodated in the buckle cover 40, and the wristwatch 100 is worn around the user's wrist. In this state, the front surface of the folding member 2 comes into contact with the restriction strip 64 of the swing arm 60. Therefore, the rotation of the swing arm 60 in the second rotational

direction R2 is restricted, and the engagement click 63 remains in engagement with a groove section 53, so that the band length is also fixed.

How to detach the wristwatch 100 from the wrist will next be described.

When the user presses the first button 71 and the second button 72, the guide surfaces 712A and 722A push the guidance surfaces 831, causing the lock member 80 to move in the direction X2 to unlock the lock member 80 from the locking surface 821.

The middle plate 20 and outer plate 30 of the folding member 2 having been folded and accommodated in the buckle cover 40 can therefore be unfolded, as shown in FIG. 11, so that the wristwatch 100 can be detached from the wrist.

How to Adjust Band Length

How to adjust the band length will next be described with reference to FIGS. 12 to 14.

In the state in which the middle plate 20 and the outer plate 30 of the folding member 2 are unfolded, the folding member 2 is not in contact with the restriction strip 64 of the swing arm 60, so that the swing arm 60 is also allowed to rotate in the second rotational direction R2. In this state, the second band 12 linked to the slide plate 50 is moved in the direction X1 or X2 relative to the buckle cover 40. Thereafter, when the first inclining surface 633 or the second inclining surface 634 of the engagement click 63 comes into contact with the first inclining surface 531 or the second inclining surface 532 of any of the groove sections 53 of the slide plate 50, the swing arm 60 rotates in the second rotational direction R2 against the urging force produced by the torsional spring 65. Thereafter, when the front end of the engagement click 63 climbs over the apex between the groove sections 53 of the slide plate 50, the urging force produced by the torsional spring 65 rotates the swing arm 60 in the first rotational direction R1 as the slide plate 50 moves, and the engagement click 63 engages with the adjacent groove section 53.

For example, when the second band 12 and the slide plate 50 are moved in the direction in which the second band 12 and the slide plate 50 are pulled out of the buckle cover 40, the second inclining surface 532 of the slide plate 50 comes into contact with the second inclining surface 634 of the engagement click 63, as shown in FIG. 12. Since the second inclining surface 532 and the second inclining surface 634 incline with respect to the direction X2, the engagement click 63 moves in the direction Z1 and the swing arm 60 rotates in the second rotational direction R2. In this case, since the swing arm 60 is urged in the first rotational direction R1 by the urging force produced by the torsional spring 65, the engagement click 63 moves while being in contact with the second inclining surface 532, as shown in FIGS. 12 and 13.

After the engagement click 63 reaches the apex of the second inclining surface 532, and when the slide plate 50 is further moved in the direction X2, the urging force produced by the torsional spring 65 rotates the swing arm 60 in the first rotational direction R1, and the engagement click 63 moves while being in contact with the first inclining surface 531. When the engagement click 63 engages with the groove section 53 of the slide plate 50, one-step movement of the position of the slide plate 50 is completed, as shown in FIG. 14. Repeating the movement described above allows adjustment of the position of the slide plate 50 to nine different positions in accordance with the number of formed groove sections 53, nine groove sections 53 in FIGS. 12 to 14. Thereafter, when the hook 21 is locked by the lock member

80, and the holding member 2 is accommodated in the buckle cover 40, the folding member 2 can restrict the rotation of the swing arm 60 in the second rotational direction R2, and can also restrict the movement of the slide plate 50, that is, the adjustment of the band length, as described above.

In the state in which the engagement click 63 engages with the groove section 53 adjacent to the movement restriction section 54, the second perpendicular surface 632 of the engagement click 63 comes into contact with the restriction surface 54A of the movement restriction section 54, so that movement of the slide plate 50 in the direction X2 is restricted, as shown in FIG. 15. Therefore, to extend the band length by moving the slide plate 50 in the direction X2, the state shown in FIG. 15, in which the engagement click 63 is in contact with the movement restriction section 54, is a maximum band length state in which the band length is maximized, and any further movement of the slide plate 50 in the direction X2 is restricted.

When the slide plate 50 is attached to the buckle cover 40 or detached from the buckle cover 40 for maintenance or other purposes, the swing arm 60 may be rotated to a position where the front end of the engagement click 63 climbs over the movement restriction section 54 by moving the restriction strip 64 of the swing arm 60 in the second rotational direction R2 with a jig or any other tool.

Effects of Embodiment

In the buckle 1, since detaching the folding member 2 from the buckle cover 40 cancels the restriction of the rotation of the swing arm 60 in the second rotational direction R2, the engagement click 63 of the swing arm 60 can be detached from the groove section 53 of the slide plate 50 to cancel the engagement. The first inclination surface 531 and the second inclination surface 532 of each of the groove sections 53 and the first inclination surface 633 and the second inclination surface 634 of the engagement click 63 each incline with respect to the direction of sliding movement. Therefore, when the slide plate 50 is caused to slide by pushing or pulling the second band 12 toward or from the buckle cover 40, the swing arm 60 can be rotated in the second rotational direction R2 against the urging force produced by the torsional spring 65. The band length can therefore be readily adjusted simply by moving the slide plate 50 without any button operation.

Furthermore, in the state in which the folding member 2 is folded and accommodated in the buckle cover 40, when the folding member 2 comes into contact with the restriction strip 64, the rotation of the swing arm 60 in the second rotational direction R2 can be restricted, whereby the engagement of the engagement click 63 with the groove section 53 can be maintained. Therefore, the state in which the slide plate 50 is not allowed to slide, that is, the band length cannot be adjusted can be achieved, whereby an unintentional increase or decrease in the band length can be reliably avoided.

Furthermore, since the buckle 1 is formed of a small number of parts, the buckle 1 can be readily assembled, and the cost of the buckle 1 can be reduced. Moreover, the band length can be adjusted in multiple steps in accordance with the number of groove sections 53 by the distance between the groove sections 53 in each step, allowing the bands to fit the user's wrist.

Providing the swing arm 60 with the restriction strip 64, and causing the folding member 2 to come into contact with the restriction strip 64 allow restriction of the rotation of the

swing arm 60 in the second rotational direction R2, whereby the simple structure can reliably prevent an increase or a decrease in the band length. In particular, since a relatively large area of the restriction strip 64 can be ensured, the contact area where the restriction strip 64 is in contact with the folding member 2 can also be a large area, allowing the restriction strip 64 to reliably come into contact with the folding member 2 and the rotation of the swing arm 60 to be reliably restricted.

10 The restriction strip 64 is disposed on the side facing the torsional spring 65 and the rear surface of the lock member 80 and can hide the torsional spring 65 and the lock member 80, whereby the buckle 1 has a simplified appearance when the rear side thereof is viewed, and the aesthetic appeal thereof can be improved. Furthermore, when the rear side of the buckle 1 is viewed, the engagement click 63 of the swing arm 60 is hidden behind the slide plate 50, and the groove sections 53 of the slide plate 50 are also not exposed to the rear side of the buckle 1, whereby the appearance of the rear side of the buckle 1 can be simplified and the aesthetic appeal thereof can be improved also in this regard.

15 The folding member 2 is provided with the hook 21, and the lock member 80, which is moved to the locked position where the hook 21 is locked and to the unlocked position where the hook 21 is unlocked, is provided. Therefore, the locked state in which the folding member 2 is folded and accommodated in the buckle cover 40 or the unlocked state in which the folding member 2 is detached from the buckle 20 cover 40 can be reliably achieved by moving the lock member 80. Since the lock member 80 moves to lock or unlock the hook 21, durability of the buckle cover can be improved as compared, for example, with a case where the locked and unlocked states are achieved by deforming the 25 sidewall sections or any other portion of the buckle cover.

30 The single torsional spring 65 serves as both the spring that urges the swing arm 60 in the first rotational direction R1 and the spring that urges the lock member 80 to the locked position. Furthermore, the first button 71 and the second button 72 are urged in opposite directions when the lock member 80 is moved to the locked position. Therefore, the number of parts can be reduced, and the assembly can be readily performed, so that the cost can be reduced as compared with the case where separate springs urge the 35 swing arm 60 and the lock member 80.

40 The engagement click 63 is configured to have a triangular shape, and the groove sections 53 are configured to each have an inverted triangular shape, that is, the shape of the letter V with which the engagement click 63 can engage. The contact surfaces where the engagement click 63 comes into contact with the groove sections 53, that is, the first inclining surface 531, the second inclining surface 532, the first inclining surface 633, and the second inclining surface 634, can therefore incline with respect to the sliding direction of the slide plate 50. Therefore, even in the state in which the engagement click 63 is urged by the torsional spring 65, when the slide plate 50 is moved in the direction X1 or X2, the engagement click 63 readily moves along the first inclining surface 531 or the second inclining surface 532 of any of the groove sections 53, whereby the slide plate 50 is allowed to readily slide. Furthermore, the first inclining surface 531 and the second inclining surface 532 have the same inclination angle, so do the first inclining surface 633 and the second inclining surface 634 correspondingly. The 45 slide plate 50 can therefore be moved in the directions X1 and X2 with a force having substantially the same magnitude. The user can therefore shorten and extend the band 50

11

length with the force having substantially the same magnitude, whereby operability of the band length adjustment can be improved.

Since the guide grooves 44 are formed in the buckle cover 40, and the plate section 51 of the slide plate 50 is inserted into the guide grooves 44, the slide plate 50 moves stably without rattling. The band length can thus be adjusted in a stable, smooth manner. The guide grooves 44 are formed in the direction X1 only to a position halfway along the first sidewall section 42 and the second sidewall section 43, whereby the movement of the slide plate 50 in the direction X1 can be restricted. The movement restriction prevents the slide plate 50 from colliding with and damaging the swing arm 60 and other components.

The slide plate 50 is provided with the movement restriction section 54, which can restrict the movement of the slide plate 50 in the direction X2. The movement restriction prevents the engagement click 63 of the swing arm 60 from coming off the slide plate 50 or the slide plate 50 from coming off the buckle cover 40 when the slide plate 50 is pulled out and the band length is adjusted.

Variations

The present disclosure is not limited to the embodiment described above, and variations, improvements, and other modifications to the extent that the advantage of the present disclosure is achieved fall within the scope of the present disclosure.

For example, a first inclining surface 531B and a second inclining surface 532B, which form each of groove sections 53B of a slide plate 50B, may have inclination angles different from each other with respect to the sliding direction, as shown in FIG. 16. For example, an inclination angle θ1 of the first inclining surface 531B is 40 degrees, and an inclination angle θ2 of the second inclining surface 532B is 60 degrees. In this case, a first inclining surface 633B and a second inclining surface 634B of an engagement click 63B of a swing arm 60B are configured to be contactable with the first inclining surface 531B and the second inclining surface 532B.

Let θ1 be the inclination angle of the first inclining surface 531B, which comes into contact with the first inclining surface 633B of the engagement click 63B when the slide plate 50B is moved in the direction X1 to shorten the band length. Let θ2 be the inclination angle of the second inclining surface 532B, which comes into contact with the second inclining surface 634B of the engagement click 63B when the slide plate 50B is moved in the direction X2 to extend the band length. Since the inclination angle θ1 is smaller than the inclination angle θ2, the slide plate 50B can be moved more readily when the band length is shortened than when the band length is extended.

The relationship in magnitude of the inclination angles between the inclining surfaces of the groove sections 53 may be reversed from the relationship in FIG. 16, in which case the slide plate 50B can be moved more readily when the band length is extended than when the band length is shortened.

The configuration that restricts the rotation of the swing arm 60 in the second rotational direction R2 is not limited to the configuration in which the restriction strip 64, which comes into contact with the folding member 2, is provided.

For example, the folding member 2 is provided with a protruding element that comes into contact with the linkage wall 612 when the folding member 2 is accommodated in the buckle cover 40 to restrict the rotation of the swing arm 60 in the second rotational direction R2. A configuration that

12

allows the rotation restriction without providing the restriction strip 64 of the swing arm 60 may therefore be employed.

The relative positional relationship between the swing arm 60 and the slide plate 50 along the axis-Z direction may be reversed. The groove sections 53 of the slide plate 50 are formed in the direction Z2, and the engagement click 63 of the swing arm 60 is caused to protrude in the direction Z1. The swing arm 60 and the slide plate 50 may be so configured that the engagement click 63 engages with the groove section 53 when the front end of the swing arm 60 moves in the direction Z1, and that the engagement click 63 disengages from the groove section 53 when the front end of the swing arm 60 moves in the direction Z2. In this case, the rotation of the swing arm 60 can be restricted by accommodating the folding member 2 in the buckle cover 40 and causing the folding member 2 to come into contact with the arm section 62 of the swing arm 60.

The configuration that locks the folding member 2 is not limited to the configuration using the hook 21 including the click 23 and the sliding lock member 80. For example, the folding member 2 may be provided with a lock pin having a shaft section and an umbrella section located at the front end of the shaft section and having a diameter greater than that of the shaft section, and a button unit provided in the buckle cover 40 may be used to lock or unlock the lock pin. That is, the folding member 2 only needs to be locked with the folding member 2 accommodated in the buckle cover 40.

In the embodiment described above, the torsional spring 65 produces the urging force for rotating the swing arm 60 and the urging force for moving the lock member 80 to the locked position, and the urging forces may instead be produced by separate springs. Furthermore, a spring that moves the lock member 80 to the locked position and a spring that urges the first button 71 and second button 72 in opposite directions may be provided separately.

The engagement click 63 of the swing arm 60 and the groove sections 53 of the slide plate 50 do not necessarily have a triangular cross section. For example, an engagement click or groove sections having an arcuate cross-sectional shape may be used. Furthermore, the movement of the slide plate may be locked when the engagement click engages with a groove section, and the movement of the slide plate may allow the swing arm to pivot when the rotation of the swing arm in the second rotational direction R2 is not restricted.

The slide plate 50 is not necessarily guided along the guide grooves 44 of the buckle cover 40. For example, concave grooves may be formed at the side surfaces of the slide plate 50, and convex guide rail portions inserted into the concave grooves of the slide plate 50 may be formed at the inner surfaces of the first sidewall section 42 and the second sidewall section 43. The slide plate 50 does not necessarily have a front end at which the movement restriction section 54 is provided.

The buckle 1 can be used not only as part of a timepiece band, but also, for example, as part of a bracelet, a necklace, and other accessory bands.

Overview of Present Disclosure

A buckle according to an aspect of the present disclosure is a buckle that links a first band and a second band to each other, the buckle including a folding member linked to the first band, a buckle cover pivotably linked to the folding member, a slide plate supported slidably relative to the buckle cover in the longitudinal direction of the first band and the second band and linked to the second band, a swing

arm rotatably supported by the buckle cover, and a spring that urges the swing arm. The slide plate has a plurality of groove sections provided along the longitudinal direction. The swing arm includes an engagement click engageable with any of the groove sections of the slide plate and is supported rotatably in a first rotational direction in which the engagement click engages with any of the groove sections and in a second rotational direction in which the engagement click separates from the groove section. The spring urges the swing arm in the first rotational direction. The folding member restricts rotation of the swing arm in the second rotational direction when the folding member is accommodated in the buckle cover, and cancels the restriction of the rotation of the swing arm in the second rotational direction when the folding member is detached from the buckle cover.

In the buckle according to the aspect of the present disclosure, when the folding member is detached from the buckle cover to cancel the restriction of the rotation of the swing arm in the second rotational direction, the engagement click of the swing arm can be separate from the groove section of the slide plate. Therefore, for example, configuring at least one of the engagement click and each of the groove sections to be an inclining surface allows the swing arm to be rotated in the second rotational direction against the urging force produced by the spring when the slide plate is caused to slide. The band length can therefore be readily adjusted simply by moving the slide plate without any button operation.

Furthermore, in the state in which the folding member is folded and accommodated in the buckle cover, rotation of the swing arm in the second rotational direction can be restricted, whereby the engagement of the engagement click with the groove section can be maintained. Therefore, the state in which the slide plate is not allowed to slide, that is, the band length cannot be adjusted can be achieved, whereby an unintentional increase or decrease in the band length can be reliably avoided.

Since the buckle is formed of a small number of parts, the buckle can be readily assembled, and the cost thereof can be reduced. Moreover, the band length can be adjusted in multiple steps in accordance with the number of groove sections by the distance between the groove sections in each step, whereby the band length can be readily fit the user's wrist or any other body site.

In the buckle according to the aspect of the present disclosure, it is preferable that the swing arm includes a base rotatably supported by the buckle cover, an arm section extending from the base toward the slide plate and provided with an engagement click, and a restriction strip extending from the base toward the side opposite to the arm section, and that rotation of the swing arm in the second rotational direction is restricted when the restriction strip comes into contact with the folding member accommodated in the buckle cover.

In the buckle according to the aspect of the present disclosure, rotation of the swing arm in the second rotational direction is restricted by providing the swing arm with the restriction strip and causing the folding member to come into contact with the restriction strip, whereby the simple structure can reliably restrict the rotation of the swing arm.

It is preferable that the buckle according to the present disclosure includes a button unit including a lock member urged by the spring and a first button and a second button protruding out of the buckle cover, that the folding member is provided with a hook, that when the lock member is urged by the spring, the lock member urges the first button and the second button in opposite directions and moves to a locked

position where the hook is locked, and when the first button and the second button are pressed, the lock member is moved against the urging force produced by the spring to an unlocked position where the hook is unlocked.

5 In the buckle according to the aspect of the present disclosure, in which the folding member is provided with the hook, and the locking member, which is moved to the locked position where the hook is locked and to the unlocked position where the hook is unlocked, is provided, the locked 10 state in which the folding member is accommodated in the buckle cover and the unlocked state can be reliably achieved, and the lock member is moved to lock and unlock the hook, whereby durability of the buckle cover can be improved as compared, for example, with a case where the 15 locked and unlocked states are achieved by deforming the sidewall sections or any other portion of the buckle cover.

Since the single spring serves as both the spring that urges the swing arm in the first rotational direction and the spring that urges the lock member to the locked position, and 20 furthermore, the first button and the second button are urged in opposite directions when the lock member is moved to the locked position, the number of parts can be reduced, and the assembly can be readily performed, so that the cost can be reduced as compared with the case where separate springs 25 urge the swing arm and the lock member.

In the buckle according to the aspect of the present disclosure, it is preferable that the engagement click of the swing arm has a triangular shape in the side view viewed in the axial direction of the axis of rotation of the swing arm, and that the groove sections of the slide plate each have an 30 inverted triangular shape with which the engagement click is engageable.

In the buckle according to the aspect of the present disclosure, the engagement click has a triangular shape, and 35 the groove sections each have an inverted triangular shape with which the engagement click can engage, whereby the contact surface where the engagement click comes into contact with any of the groove sections can incline with respect to the sliding direction of the slide plate. Therefore, 40 even in the state in which the engagement click is urged by the spring, when the slide plate is moved in either the direction in which the slide plate is pushed into or pulled from the buckle cover, the engagement click can readily move along the inclining surface of each of the groove sections, whereby the slide plate can be readily caused to slide to adjust the band length when the rotation of the swing arm is not restricted.

In the buckle according to the aspect of the present disclosure, it is preferable that the groove sections of the slide plate each have a first inclining surface with which the engagement click comes into contact when the slide plate is moved in the direction in which the slide plate approaches the axis of rotation of the swing arm and a second inclining surface with which the engagement click comes into contact 50 when the slide plate is moved in the direction in which the slide plate moves away from the axis of rotation of the swing arm, and that the inclination angle of the first inclining surface with respect to the direction of the movement of the slide plate is smaller than the inclination angle of the second inclining surface with respect thereto.

In the buckle according to the aspect of the present disclosure, since the inclination angle of the first inclining surface with respect to the direction of the movement of the slide plate is smaller than the inclination angle of the second 55 inclining surface with respect thereto, the slide plate can be moved more readily when the slide plate is moved in the direction in which the slide plate approaches the axis of

15

rotation of the swing arm, that is, when the band length is shortened than when the slide plate is moved in the opposite direction, that is, when the band length is extended.

In the buckle according to the present disclosure, it is preferable that the buckle cover includes a front surface section, a first sidewall section, and a second sidewall section, that guide grooves extending along the longitudinal direction are formed at the inner surfaces of the first sidewall section and the second sidewall section, and that the slide plate includes a plate section inserted into the guide grooves.

The buckle according to the present disclosure, in which the plate section of the slide plate is inserted into the guide grooves so that the slide plate moves stably, allows stable, smooth adjustment of the band length. Furthermore, since the range over which the slide plate moves can be set by the guide grooves, damage to other parts due to collision of the slide plate with the other parts can also be suppressed.

In the buckle according to the present disclosure, it is preferable that the slide plate includes a movement restriction section provided continuously with the groove sections, that the movement restriction section has a restriction surface perpendicular to the sliding direction of the slide plate and protruding beyond the groove sections, and that the engagement click has a perpendicular surface that comes into contact with the restriction surface.

In the buckle according to the present disclosure, the perpendicular surface of the engagement click of the swing arm comes into contact with the restriction surface, whereby the movement of the slide plate can be restricted. The movement restriction prevents the engagement click of the swing arm from coming off the slide plate when the slide plate is moved to adjust the band length.

A timepiece according to another aspect of the present disclosure includes the buckle described above.

The timepiece according to the other aspect of the present disclosure, which includes the buckle described above, can provide the effects described above, readily allows the band length adjustment, and is applicable to a variety of timepieces.

What is claimed is:

1. A buckle that links a first band and a second band to each other, the buckle comprising:
a folding member linked to the first band;
a buckle cover pivotably linked to the folding member;
a slide plate supported slidably relative to the buckle cover in a longitudinal direction of the first band and the second band and linked to the second band;
a swing arm rotatably supported by the buckle cover; and
a spring that urges the swing arm,
wherein the slide plate has a plurality of groove sections provided along the longitudinal direction,
the swing arm includes an engagement click engageable with any of the groove sections of the slide plate and is supported rotatably in a first rotational direction in which the engagement click engages with any of the groove sections and in a second rotational direction in which the engagement click separates from the groove section,
the spring urges the swing arm in the first rotational direction, and
the folding member restricts rotation of the swing arm in the second rotational direction when the folding member is accommodated in the buckle cover, and cancels the restriction of the rotation of the swing arm in the

16

second rotational direction when the folding member is detached from the buckle cover.

2. The buckle according to claim 1,
wherein the swing arm includes a base rotatably supported by the buckle cover, an arm section extending from the base toward the slide plate and provided with the engagement click, and a restriction strip extending from the base toward a side opposite to the arm section, and

rotation of the swing arm in the second rotational direction is restricted when the restriction strip comes into contact with the folding member accommodated in the buckle cover.

3. The buckle according to claim 1,
further comprising a button unit including a lock member urged by the spring and a first button and a second button protruding out of the buckle cover,
wherein the folding member is provided with a hook, and when the lock member is urged by the spring, the lock member urges the first button and the second button in opposite directions and moves to a locked position where the hook is locked, and when the first button and the second button are pressed, the lock member is moved against an urging force produced by the spring to an unlocked position where the hook is unlocked.

4. The buckle according to claim 1,
wherein the engagement click of the swing arm has a triangular shape in a side view viewed in an axial direction of an axis of rotation of the swing arm, and the groove sections of the slide plate each have an inverted triangular shape with which the engagement click is engageable.

5. The buckle according to claim 4,
wherein the groove sections of the slide plate each have a first inclining surface with which the engagement click comes into contact when the slide plate is moved in a direction in which the slide plate approaches the axis of rotation of the swing arm, and
a second inclining surface with which the engagement click comes into contact when the slide plate is moved in a direction in which the slide plate moves away from the axis of rotation of the swing arm, and
an inclination angle of the first inclining surface with respect to a direction of the movement of the slide plate is smaller than an inclination angle of the second inclining surface with respect thereto.

6. The buckle according to claim 1,
wherein the buckle cover includes a front surface section, a first sidewall section, and a second sidewall section, guide grooves extending along the longitudinal direction are formed at inner surfaces of the first sidewall section and the second sidewall section, and
the slide plate includes a plate section inserted into the guide grooves.

7. The buckle according to claim 1,
wherein the slide plate includes a movement restriction section provided continuously with the groove sections, the movement restriction section has a restriction surface perpendicular to a sliding direction of the slide plate and protruding beyond the groove sections, and the engagement click has a perpendicular surface that comes into contact with the restriction surface.

8. A timepiece comprising the buckle according to claim 1.
